Primary Examiner — Karen E Eldridge Powers

(57) CLAIM

The ornamental design for a combination electric toothbrush and toothbrush charger, as shown and described.

DESCRIPTION

The patent or application file contains at least one drawing executed in color. Copies of this patent or patent application publication with color drawing(s) will be provided by the Office upon request and payment of the necessary fee.

1. Combination electric toothbrush and toothbrush charger
- 1.1 is a perspective view of the claimed design;
- 1.2 is a front view of the claimed design;
- 1.3 is a back view of the claimed design;
- 1.4 is a left side view of the claimed design;
- 1.5 is a right side view of the claimed design;
- 1.6 is a top view of the claimed design; and
- 1.7 is a bottom view of the claimed design.

1 Claim, 7 Drawing Sheets
(7 of 7 Drawing Sheet(s) Filed in Color)
